(57) **CLAIM**

The ornamental design for a camouflage pattern for sheet goods, as shown and described.

DESCRIPTION

The FIGURE is a plan view of a camouflage pattern for sheet goods showing my design.

The broken line border is indicative of indeterminate size and shape and is no part of the claimed Design. It is to be understood that coloration and color combinations of the pattern as well as scale of the repeat unit may be varied.

The varying patterns of gray tones and dots are understood to represent contrasting colors.
